ATTORNEY

DESIGN FOR A SADDLE-SEAT.

SPECIFICATION forming part of Design No. 27,616, dated August 31, 1897.

Application filed July 21, 1897. Serial No. 645,472. Term of patent 7 years.

To all whom it may concern:

Be it known that I, HENRY A. RUSCH, a citizen of the United States, residing at Newark, in the county of Essex and State of New Jersey, have invented a certain new and useful Design for Saddle-Seats, of which the following is a full, clear, and exact description of the invention, such as will enable others skilled in the art to which it appertains to make and use the same, reference being had to the accompanying drawings, and to letters of reference marked thereon, which form part of this specification.

The invention relates to a new and original design for a saddle-seat for bicycles, velocipedes, and other vehicles; and the design consists, essentially, of the seat portion of the saddle, which in general outline has the ornamental appearance of a palm-leaf provided with a pair of raised portions which terminate in a centrally-raised part at the front of the seat, forming the pommel, but having between said raised portions an ornamental depression extending longitudinally from a point near the pommel to the rear end of the seat, whereby the whole when viewed from the top receives an emarginate or cordate appearance, besides the palm-leaf shape hereinabove mentioned.

The invention consists, furthermore, in the other ornamental features hereinafter described, such as the downwardly-flaring lower surfaces and rear edge of the saddle-seat and the ornamental stitching, all of which will be fully understood by reference to the accompanying drawings, in which my novel design for a saddle-seat for bicycles, velocipedes, and other wheeled vehicles is clearly illustrated.

In said drawings, Figure 1 is a top or plan view of the saddle-seat, showing my novel design. Fig. 2 is a rear end view of the same, and Fig. 3 is a cross-section taken on line α in Fig. 1.

As illustrated in said drawings, A indicates the main body of the saddle-seat, which is entirely surrounded or bounded by the curved edge α , formed by the elliptically-curved margin α' , α^2 , and α^3 at the rear and opposite sides, the inwardly and slightly-outwardly curved margins α^4 , α^5 on opposite sides of the

seat, and the curved marginal end portion α^6 of the pommel, which together are approximately of the configuration or outline of a palm-leaf. The upper surface of the saddle-seat is formed with a pair of raised portions c and c' and an ornamental depression b between them, bounded by the curved outlines c^2 and the arc-shaped portions c^3 of said raised portions c and c' . Said portions c and c' are also bounded by the marginal curves c^4 , c^5 , and c^6 , which approximately correspond to the general outline of the saddle-seat and whereby an ornamental flat narrow ledge is provided upon the upper surface of the seat along its marginal outline, as clearly represented in the several figures of the drawings. Said raised portions c and c' are both surrounded by the gently-tapering and arc-shaped curved surfaces c^7 and c^8 , having also the slightly-curved upper surfaces c^9 , as more clearly indicated in Figs. 2 and 3, and terminating at the front of the saddle-seat in the slightly upwardly-projecting pommel c^9 . The saddle is ornamented with a row of stitching e at or near the entire marginal edge of the main body portion A and with a row of stitching e^1 of the ornamental outline of the depression b between the two raised parts c and c' , as will be seen from an inspection of Fig. 1.

When viewed from the rear, the saddle-seat has a curved appearance at α^7 and has the oppositely and downwardly flaring parts α^8 and α^9 , the under surfaces of the seat portion being perfectly flat and having a longitudinal channel-shaped formation α^{10} at the points where said parts meet, as clearly indicated in Figs. 2 and 3.

It will thus be seen that the leading features of my novel design reside in a saddle-seat having the general outline of a palm-leaf, with the ornamental raised parts c and c' terminating in a slightly-raised pommel, a centrally and longitudinally disposed depression bounded by the curved lines, as herein stated and shown, whereby the seat when viewed from the top has an emarginate or approximate heart-shaped appearance, bounded by the ornamental outer marginal edge, which is flat on top and slightly rounded on its outer surface, and the main parts of the saddle-seat

flaring downwardly and laterally on opposite sides of the longitudinal central axis of the seat and being flat on the under side.

Having thus described my novel design for a saddle-seat for bicycles, velocipedes, and other vehicles, what I claim is—

The design for a saddle-seat, substantially as herein shown and described.

In testimony that I claim the invention set forth above I have hereunto set my hand this 19th day of July, 1897.

HENRY A. RUSCH.
